UNITED STATES PATENT OFFICE.

HENRY W. N. COLE, OF BROOKLYN, NEW YORK.

ROTARY-CYLINDER INTERNAL-COMBUSTION ENGINE.

1,215,778.

Specification of Letters Patent. Patented Feb. 13, 1917.

Application filed February 11, 1916. Serial No. 77,578.

To all whom it may concern:
Be it known that I, HENRY W. N. COLE, a citizen of the United States of America, and a resident of Brooklyn, Kings county, 5 and State of New York, have invented certain new and useful Improvements in Rotary-Cylinder Internal-Combustion Engines, of which the following is a specification, reference being had to the accompanying drawings, forming a part thereof.

My invention relates to improvements in rotary cylinder internal combustion engines, and its object is to provide an engine of this type which shall be simple in construction 15 and efficient in operation, and free from the objectionable features which have necessarily detracted from the engines of this type which have been used or proposed heretofore.

20 Other objects of this invention are to provide a valveless engine into which the supply of combustible mixture may be led and from which the burnt gases may be removed completely in a simple and direct manner 25 without producing undesirable side pressures and without producing internal deposits of carbon; to provide in a simple manner for expansion due to heat; to provide an efficient cooling arrangement and means 30 for regulating it; to provide for the automatic firing of the compressed gases, and to properly lubricate the apparatus with a minimum amount of oil.

These and other objects of the invention 35 will appear in the following specification in which I will describe my invention and then point out the novel features thereof in appended claims.

Referring to the drawings:
40 Figure 1 is a sectional end elevation of an engine, embodying my invention, the view being taken on the line 1—1 of Fig. 3.

Fig. 2 is a sectional end elevation, principally through the center of the engine as 45 indicated by the line 2—2 of Fig. 3, some of the parts being shown in true section, some partially sectioned and some covered by broken-away portions which lie in front of the sectional plane.

50 Fig. 3 is a sectional side elevation of the engine, the section being taken on the two intersecting planes indicated by the line 3—3 in Fig. 1.

The arrangement of intake and exhaust 55 ports is shown in Fig. 4 which is a development of a section taken on the curved line

4—4 of Fig. 1 looking in the direction of the arrows.

A somewhat similar development of a section taken on the line 5—5 of Fig. 1, illustrates in Fig. 5, the arrangement of spark plugs and of channels which serve to connect adjacent cylinders when the engine is running.

Fig. 6 is a sectional end elevation of one 65 side of the engine, the section being taken on the line 6—6 of Fig. 3, looking in the direction of the arrows and in this figure a sector-like fragment of the rotor is shown which lies between the sectional plane and 70 the center of the engine.

In Fig. 7 a sectional elevation of the other side of the engine is illustrated, the section being taken on the line 7—7 of Fig. 3 in the direction of the arrows which it 75 will be noted point in the opposite direction to those on the line 6—6 of the same figure.

Fig. 8 is a side elevation of a part of the engine, the view being taken from the line 80 8—8 of Fig. 6, with one of the cylinders in place and with its cylinder head broken away to more clearly show the construction.

Fig. 9 is a sectional side elevation of a 85 part of the engine, the section being taken on the line 9—9 of Fig. 6.

Like characters of reference designate corresponding parts in all the figures.

10 and 20 designate side plates which form the frame of the engine. These are substantially circular and are connected and held at a desired distance from one another by a plurality of equally spaced tie-bolts 11. Angle brackets 12—12 are affixed to the lower parts of these side plates to form a base for 95 the engine.

The side plate 10 is constructed to form a central hub 13 which supports a circular roller track 14 for supporting the rotor, and contains a hole 15 below the center of this 100 track for eccentrically supporting a piston pin. It is also provided with a plurality of radial strengthening ribs 16 and a circular ring of air openings 17. The latter may be closed or partly closed by a rotary shutter 105 30 which is provided with openings corresponding in size, shape and relative positions with the openings 17, and also provided with slots 31 which lie in a common circle and through which pass screws 32 by 110 means of which the shutter is supported upon the inner face of the side plate 10 and

yet is capable of being given a limited rotation in respect of the side plate.

18 is an annular recess in the inner face of the side plate 10, which receives certain valve plates which will be described fully hereinafter. 19 is an exhaust chamber formed integrally with the side plate 10.

The other side plate 20 is constructed with a central flanged opening 21 into which 10 fits the end of the rotor bearing 22 which is secured to the side plate by the bolts 23 and which supports the hollow cylindrical roller track 24. The side plate has strengthening ribs 25 and is provided with two rings of 15 air openings 26-27. It has an annular recess 28 opposite the recess 18 in side plate 10, an exhaust chamber 29, opposite exhaust chamber 19, but somewhat shorter than the latter, and an intake chamber 40 in circumferential alignment with the chamber 29.

Back of these openings is a shutter 33 which like the shutter 30, is provided with openings corresponding in size, shape and relative positions with the air openings in 25 the side plate on which it is mounted. This shutter is also provided with slots 34 between its openings which slots lie in a common circle and through them pass screws 35 by means of which the shutter is mounted 30 upon the inner face of the side plate 20 and yet is capable of being given a limited rotation in respect of the side plate. 36 is a bail-like strap, one end of which is connected with shutter 30 at 37, and the other end of which is connected with shutter 33 at 38. When not in use this rests upon the tie-bolt 11^a which is extended on both sides of the apparatus for the purpose of supporting it.

40 By means of this strap the shutters 30 and 33 may be adjusted simultaneously to close the air openings 17, 26 and 27, or to open them to any desired extent.

41 is a carbureter which is connected with 45 the intake chamber 40 by a pipe 42. A fan 43 is incorporated in the carbureter which is driven by a belt 44 from the rotor shaft.

The rotor shaft is designated by 50 and is mounted as shown to run on rollers in the bearing 22. The rotor frame runs between the two side plates 10 and 20. One side of this, designated by 51, is constructed with a hollow circular part 52 which runs on rollers on the side plate hub 13, and the other side 55 53 is provided with a central hub 54 which is affixed to the rotor shaft 50. The outer part or periphery of the rotor frame is split as shown at 57, and bolts 55 are provided under the heads of which are springs 56 which allow for expansion of this part of the cylinders which are held in the rotor frame. Through the split periphery of the rotor frame are a plurality of radially disposed circular holes which are bored through 60 an inner ring 58 and into which cylinders

proper which are members designated by 60, preferably of tubular steel, clamped between these split portions of the periphery by the bolts and springs 55-56, and further secured to the rotor frame by pins 61. Inside of this peripheral part of the rotor frame are lugs 59 through which pass small ports 90-90. Between the lugs 59 and the perforated ring 58 are intermediate projections 59^a through which pass ports 75 93-93 and between projections 59^a and the perforated ring, the rotor frames are provided with openings 50^b which are opposite the air openings 17 and 27.

The cylinder heads 62 are fastened to both 80 sides of the split periphery directly by means of bolts 63. Between the cylinders are interposed spaced air blades or vanes 64 which are affixed to both sides of the rotor frame.

In the annular groove 28 in the side plate 20 is an annular port ring 65, held in place by bolts 66. The inner surface of the ring is flat and that portion of the rotor frame side 58 through which pass the ports 90 and 93 are pressed against it. This port ring is provided with a plurality of openings 67 which communicate with the exhaust chamber 29 and in alignment therewith similar openings 68 which communicate with the 95 intake chamber 40. It is also provided with a groove 69 of sufficient length to reach from the port 90 from one cylinder to the similar port from the adjacent cylinder.

In the rotor frame side 51 are two port rings 70 and 74. The first of these is pressed against the rotor and presses the rotor against port ring 65 by springs 71 and bolts 72. This ring has a groove 73 opposite and similar to the groove 69. The ring 74 is 100 also pressed against the rotor by springs 75 and bolts 76, and this pressure also serves to press the rotor frame against the port ring 65. The backs of all of the port rings are recessed as shown. The port ring 74 has 105 a series of exhaust openings opposite the exhaust openings 67 and into them are screwed pipe nipples 77 which fit into and pass through registering openings in the side plate 10 and lead into the exhaust chamber 18 from which leads the exhaust pipe 78. 79 is a similar exhaust pipe leading from the 110 exhaust chamber 29 on the other side of the engine.

The object of the construction of the exhaust ports shown is to prevent carbonization in the space between the port rings 70-74 and the side plate 10.

80 is a power transmission ring which rotates about an eccentric pin 81, one end of 125 which is supported in the opening 15 in side plate 10 and the other end of which is supported by a hanger bracket 82 which has a boss 83 projecting into the end of the rotor shaft 50.

The pistons are designated by 84. One of these—the one shown in the lowermost position in the drawings—is connected rigidly with the ring 80 by a connecting rod 85. The others are connected with the ring 80 by connecting rods 86 and wrist pins 87 which pass through the connecting rods and lugs on the ring and also through a collar 88 which thus becomes a part of the ring.

10 On the top of each piston is a baffle plate 89.

Near the upper part of each cylinder 60 are two diametrically opposed ports 91 which register with the ports 90 in the rotor frame. Below these are two other ports 15 92 which register with the ports 93.

It may be seen that the piston in the uppermost cylinder is as far out of the cylinder as it can go, and that in this position it uncovers the ports 92, 93. In this position, as may be seen from Fig. 4, these ports are then in communication with both the exhaust and the inlet chambers. But as the rotor moves in the direction of the arrow, communication with the exhaust is 20 cut off while communication with the inlet chamber remains. The supply is admitted under sufficient pressure to cause the cylinder to be filled with a combustive mixture during the period of this communication.

25 At about the time the port 93 runs out of communication with the last of the ports 68 from the intake chamber, the cylinder will be nearer the eccentrically set pin or shaft 81 and consequently its piston will be forced inwardly a sufficient amount to close the ports 92. As the rotation continues, the piston is forced in farther during the first half revolution, or until the position of the lowermost cylinder has been reached, and 30 during this half revolution the charge of gases has been compressed. At about this time the ports 91 come into register with the ends of grooves 69, 73 at which ends are the spark plugs 94, and when energized at 35 this time they will cause the ignition of the compressed charge in the cylinder. 98 is a diagrammatic representation of a timer for the spark plugs.

The next half stroke is the expansion 40 stroke and takes place while the piston is forced out of its cylinder by the pressure of the gases, thus driving the rotor and developing power.

When the ports 93 reach the first ports 45 67 and 77, the exhaust gases rush out through pipes 78, 79 on both sides of the engine so that no unequal side pressure is caused thereby. There are four of these exhaust ports on each side, as may be seen from Fig. 4, and a fifth on one side opposite the first of the intake ports 68. The pressure of the intake gases rushing in and deflected by the baffle plate 89 serves to expel any remaining spent gases from the cylinder, and this scavenging is aided by the first or highest pres-

sure exhaust from the next succeeding cylinder blowing through the first pipe nipple 77 into the exhaust pipe 78 which produces an ejector effect and draws out from the exhaust chamber 19 and the preceding cylinder which is still in communication with the chamber, the remainder of the exhausted gases. Thus the cylinder at the beginning of the compression stroke is filled with clean, live gas.

70 The spark plugs, as has been shown, serve to ignite the charge after compression, but their use is needed only for starting. After starting, some of the burning hot gases from each cylinder are led back to the following cylinder through the channels 69, 73, and these serve to ignite the charge in said following cylinder.

The pressure for the explosive mixture may be from any desired source. I prefer 85 to use a supply of compressed air, for this then may be utilized not only for the pressure of the explosive mixture but also for the actual starting of the rotor itself, which is accomplished by admitting the compressed air to the cylinders when they are in the 90 positions occupied by them in running during the expansion stroke of their pistons. After the engine is started a sufficient pressure for the explosive mixture is attained 95 from the fan 43.

I have shown the intake on one side only and have explained the advantages of such an arrangement. The intake may, if desired, be arranged on both sides of the rotor 100 in a similar manner to that provided for the exhaust.

The lubrication of the engine is provided for by means of an oil scoop 95 into which oil is driven by the rotation of the engine, and forced out through a pipe 96 to and through a cooler (not shown) and back into the engine through a pipe 97. The inside of the rotor is entirely inclosed as the ring 58 is continuous save for the perforations 105 therein which are filled by the cylinders so that it is possible to have this space filled with oil. It is also possible to provide oil cups on the side plates 10 and 20 with leads to the bearing faces of the port rings.

110 I have shown and described a form of engine which at present I consider one of the best designs which embodies the various improvements which I have made, but the novel features herein set forth may be incorporated in structures of other designs and I intend no limitations other than those imposed by the appended claims.

The tubular cylinders shown and described are also a preferred construction, but 115 I do not intend to limit myself to this construction except in such claims as are specifically drawn to cover it, but the intended meaning of such claims as specify a rotor frame adapted to hold cylinders and cylin- 120 125

ders therein, is that such cylinders may be held in the manner shown and described, or in any other manner, as for example, by being cast integrally with the frame.

5. What I claim is:

1. In a multi-cylinder rotary internal combustion engine, a rotor frame adapted to hold a radial series of cylinders, a plurality of cylinders arranged to rotate with the frame about a central axis, a shaft eccentrically disposed in relation to said axis, pistons in the cylinders connected with the shaft, the periphery of the rotor frame being split, and resilient means for pressing the divided periphery of the rotor frame together and against the cylinders.
2. In a multi-cylinder rotary internal combustion engine, a rotor frame adapted to hold a radial series of cylinders, said frame having a periphery and an inner ring both provided with a plurality of radial circular holes, a plurality of tubular cylinders therein arranged to rotate with the frame about a central axis, a shaft eccentrically disposed in relation to said axis, pistons in the cylinders connected with the shaft, said rotor frame periphery being split, resilient means for pressing the divided periphery of the rotor frame together and against the cylinders, and cylinder heads affixed to the periphery of the rotor frame on both sides thereof.
3. In a multi-cylinder rotary internal combustion engine, a casing comprising two connected side plates, a rotor frame adapted to hold a radial series of cylinders, a plurality of cylinders in said frame arranged to rotate with the frame about a central axis, a shaft eccentrically disposed in relation to said axis, pistons in the cylinders connected with the shaft, said rotor frame and cylinders being provided with registering ports, and port rings in said side plates at the sides of the rotor frame, said port rings being provided with ports adapted to coöperate with the ports in the rotor frame.
4. In a multi-cylinder rotary internal combustion engine, a casing comprising two connected side plates, a rotor frame adapted to hold a radial series of cylinders, a plurality of cylinders in said frame arranged to rotate with the frame about a central axis, a shaft eccentrically disposed in relation to said axis, pistons in the cylinders connected with the shaft, said rotor frame and cylinders being provided with registering ports, a port ring affixed to one of the side plates, another port ring supported by the other side plate, and means for pressing said other port ring against the rotor frame and thereby pressing the rotor frame against the first mentioned port ring, said port rings being provided with ports adapted to coöperate with the ports in the rotor frame, and said pistons being arranged in their movement to control the cylinder ports.
5. In a multi-cylinder rotary internal

combustion engine, a casing comprising two connected side plates, a flat-sided rotor frame adapted to hold a radial series of cylinders, a plurality of tubular cylinders in said frame arranged to rotate with the frame about a central axis, a shaft eccentrically disposed in relation to said axis, pistons in the cylinders connected with the shaft, said rotor frame and cylinders being provided with registering ports, a flat-faced port ring affixed to one of the side plates, another flat-faced port ring supported by the other side plate, and resilient springs for pressing said other port ring against the rotor frame and thereby pressing the rotor frame against the first mentioned port ring, said port rings being provided with ports adapted to coöperate with the ports in the rotor frame.

6. In a multi-cylinder rotary internal combustion engine, a casing comprising two connected side plates, a rotor frame adapted to hold a radial series of cylinders, a plurality of cylinders in said frame arranged to rotate with the frame about a central axis, a shaft eccentrically disposed in relation to said axis, pistons in the cylinders connected with the shaft, said rotor frame and cylinders being provided with registering ports, and port rings in said side plates at the sides of the rotor frame, said port rings being provided with ports adapted to coöperate with the ports in the rotor frame, and said pistons being arranged in their movement to control the cylinder ports.

7. In a multi-cylinder rotary internal combustion engine, a casing comprising two connected side plates, a rotor frame adapted to hold a radial series of cylinders, a plurality of cylinders in said frame arranged to rotate with the frame about a central axis, a shaft eccentrically disposed in relation to said axis, pistons in the cylinders connected with the shaft, said rotor frame and cylinders being provided with registering ports, a port ring affixed to one of the side plates, another port ring supported by the other side plate, and means for pressing said other port ring against the rotor frame and thereby pressing the rotor frame against the first mentioned port ring, said port rings being provided with ports adapted to coöperate with the ports in the rotor frame, and said pistons being arranged in their movement to control the cylinder ports.

8. In a multi-cylinder rotary internal combustion engine, a casing comprising two connected side plates, a rotor frame adapted to hold a radial series of cylinders, a plurality of cylinders arranged to rotate with the frame about a central axis, a shaft eccentrically disposed in relation to said axis, pistons in the cylinders connected with the shaft, said rotor frame and cylinders being provided with firing ports and with other

- ports for intake and exhaust ports in the rotor frame, and with a groove adapted to connect the firing port of one cylinder with the firing port of the adjacent cylinder, and 5 said pistons in their movement being arranged to control the cylinder intake and exhaust ports.
9. In a multi-cylinder rotary internal combustion engine, a casing comprising two connected side plates, a rotor frame adapted to hold a radial series of cylinders, a plurality of cylinders in said frame arranged to rotate with the frame about a central axis, a shaft eccentrically disposed in relation to 10 said axis, pistons in the cylinders connected with the shaft, said rotor frame and cylinders being provided with registering ports, a port ring supported by one of said plates, a port ring supported by the other side 15 plate, and resilient springs for pressing said other port ring against the rotor frame and thereby pressing the rotor frame against the first mentioned port ring, said port rings being provided with ports adapted to cooperate with the ports in the rotor frame, and pipe nipples affixed to the ports in the 20 spring-pressed port ring and passing through a portion of the adjacent side plate.
10. In a multi-cylinder rotary internal combustion engine, a casing comprising two connected side plates, a series of circumferentially aligned exhaust ports formed in one of said side plates and a plurality of circumferentially aligned intake ports formed 25 in the other of said side plates, said series of intake ports overlapping the series of exhaust ports, and a rotor comprising a radial series of cylinders constructed with diametrically opposed ports adapted to 30 coact with said intake and exhaust ports.
11. In a multi-cylinder rotary internal combustion engine, a casing comprising two connected side plates, a series of circumferentially aligned exhaust ports formed in one of said side plates and a plurality of circumferentially aligned intake ports formed 35 in the other of said side plates, said series of intake ports overlapping the series of exhaust ports, and a rotor comprising a radial series of cylinders constructed with diametrically opposed ports adapted to 40 coact with said intake and exhaust ports.
12. In a multi-cylinder rotary internal combustion engine, a casing comprising two connected side plates, a series of circumferentially aligned exhaust ports formed in one of said side plates and a plurality of circumferentially aligned intake ports formed 45 in the other of said side plates, said series of intake ports overlapping the series of exhaust ports, and a rotor comprising a radial series of cylinders constructed with diametrically opposed ports adapted to coact with 50 said intake and exhaust ports; and pistons in said cylinders adapted to control said cylinder ports.
13. In a multi-cylinder rotary internal combustion engine, a casing comprising two connected side plates, one of said side plates being provided with an exhaust chamber having an exhaust pipe leading outwardly 55 therefrom and a series of circumferentially aligned exhaust ports leading inwardly therefrom, the first of said series of exhaust ports being opposite said exhaust pipe, the other side plate being constructed with an intake 60 chamber and a series of circumferentially aligned ports leading inwardly therefrom, the first of said intake ports being opposite the last of said exhaust ports, a rotor comprising a radial series of cylinders constructed with diametrically opposed ports 65 adapted to coact with said intake and exhaust ports, and pistons in said cylinders adapted to control said cylinder ports.
14. In a multi-cylinder rotary internal combustion engine, a casing comprising two connected side plates, one of said side plates being provided with an exhaust chamber having an exhaust pipe leading outwardly 70 therefrom and a series of circumferentially aligned exhaust ports leading inwardly therefrom, the first of said series of exhaust ports being opposite said exhaust pipe, the other side plate being constructed with an intake 75 chamber and a series of circumferentially aligned ports leading inwardly therefrom, the first of said intake ports being opposite the last of said exhaust ports, a rotor comprising a radial series of cylinders constructed with diametrically opposed ports 80 adapted to coact with said intake and exhaust ports, and pistons in said cylinders adapted to control said cylinder ports.
15. In a multi-cylinder rotary internal combustion engine, a casing comprising two connected side plates, one of said side plates being provided with an exhaust chamber having an exhaust pipe leading outwardly 85 therefrom and a series of circumferentially aligned exhaust ports leading inwardly therefrom, the first of said series of exhaust ports being opposite said exhaust pipe, the other side plate being constructed with an intake chamber and a series of circumferentially aligned ports leading inwardly therefrom, the first of said intake ports being opposite the last of said exhaust ports, a rotor comprising a radial series of cylinders constructed with diametrically opposed ports 90 adapted to coact with said intake and exhaust ports, and pistons in said cylinders adapted to control said cylinder ports.
16. In a multi-cylinder rotary internal combustion engine, a casing comprising two connected side plates, one of said side plates being provided with an exhaust chamber having an exhaust pipe leading outwardly 95 therefrom and a series of circumferentially aligned exhaust ports leading inwardly therefrom, the first of said series of exhaust ports being opposite said exhaust pipe, the other side plate being constructed with an intake chamber having an exhaust pipe leading outwardly 100 therefrom and a series of circumferentially aligned exhaust ports leading inwardly therefrom, the first of said intake ports being opposite the last of said exhaust ports, a rotor comprising a radial series of cylinders constructed with diametrically opposed ports 105 adapted to coact with said intake and exhaust ports, and pistons in said cylinders adapted to control said cylinder ports.
17. In a multi-cylinder rotary internal combustion engine, a casing comprising two connected side plates, one of said side plates being provided with an exhaust chamber having an exhaust pipe leading outwardly 110 therefrom and a series of circumferentially aligned exhaust ports leading inwardly therefrom, the first of said intake ports being opposite the last of said exhaust ports in said first mentioned side plate, a rotor comprising a radial series of cylinders constructed with diametrically opposed ports adapted to coact with 115 said intake and exhaust ports, the port in one cylinder being adapted to reach the first of the exhaust ports before the port of the preceding cylinder has left the last of the exhaust ports, and pistons in said cylinders adapted to control said cylinder ports.

In witness whereof, I have hereunto set my hand this 9 day of February, 1916.

HENRY W. N. COLE.
